UNITED STATES PATENT OFFICE.

HANS SCHWEITER, OF HORGEN, NEAR ZURICH, SWITZERLAND.

TENSION DEVICE FOR COP-WINDERS.

1,178,954.

Specification of Letters Patent. Patented Apr. 11, 1916.

Application filed February 21, 1914. Serial No. 820,240.

To all whom it may concern:

Be it known that I, HANS SCHWEITER, a subject of the Swiss Confederation, residing at No. 525 Lindenstrasse, Horgen, near Zurich, Switzerland, have invented certain new and useful Improvements in and Relating to Tension Devices for Cop-Winders, of which the following is a specification.

Cross cop winding frames are known in which the thread is subjected to greater tension, when winding the cop points, than when winding other parts of the cop. This results in the thread being wound tightly on the tips of the cop, thereby preventing the layers of thread from slipping off. The increased tension is produced, in the known frames, by the fact that the thread being wound on the cop point is drawn out by an auxiliary thread tensioner, so that the thread in forming the cop point has to travel an increased distance. This, however, has the result that the thread nearly always rubs against the auxiliary tensioner at the same place, and thus necessitates frequent renewal of this part. The thread also suffers by the repeated change of its course and is very liable to break. These drawbacks are avoided in the present invention by the thread being braked with varying force before passing onto the cop.

One form of construction is shown in the accompanying drawing, representing so much of the apparatus as is necessary for understanding the invention.

Figure 1 is a side view of part of the machine. Fig. 2 a front view, and Fig. 3 a section on the line A—B of Fig. 1.

1 designates the spindle, which carries the cop 2 and is rotated at high speed from the driving shaft 3 by toothed gears 4, 5. The shaft 3 drives by means of gears 6, 7 a shaft 8, which carries a disk 9 provided with a cam groove in which engages a roller 10 carried by a sleeve 11 slidably mounted inside the support 12. The sleeve 11 is loose on the spindle 1, and during rotation of the disk 9 it imparts a reciprocating movement to the spindle 1 by known means. The spindle 1 and shafts 3 and 8 are mounted in the support 12, the latter being carried on a casing 27 fixed to the frame of the machine.

The thread 16 to be wound on the cop is wound from the source of supply, for example a reel, whence it passes over a guide wheel 14 carried by a lever 13 pivoted to

the casing 27, and thence between two brake disks 15, 28 to the thread guide 17 and cop 2. The two brake disks 15 and 28 are loosely mounted on a pin 19 carried by an arm 18, which is fixed on a sleeve 21 bolted to the casing 27. A rod 22, rotatable in the sleeve 21 carries at one end an arm forked at the top and engages with its other cranked end a cam 24 fixed on the shaft 8 carrying the cam 9. Thus at every revolution of the shaft 8 the forked arm 23 is pressed once against the brake disk 28, so that the thread 16 passing between the latter and the disk 15 is periodically subjected to increased brake action. The brake disk 15 abuts against a spring 25 on the pin 19, and the tension of the spring is adjustable by a nut 26 to enable the pressure on the thread to be regulated as required.

As previously mentioned, the spindle 1 and cop 2 are reciprocated by the cam disk 9, the thread is thus caused to run on the point of the cop when the spindle is in its inner position. The position of the cam 24 with respect to the cam 9 is such that when the spindle is in its inner position, so that the thread runs onto the point of the cop, the cam 24 and arm 23 cause the brake disk 16 to be pressed against the tension disk 15 whereby the tension is increased. This has the effect that the winding of the thread on the point of the cop is comparatively hard, thereby preventing the last convolutions from dropping off during the wearing.

I claim:

1. In a cop winding machine, a thread brake and means for manually adjusting the pressure of the brake, and other means cooperating with said first means to automatically increase the tension on the thread when forming the point of the cop while the path of the thread over said brake is practically retained.

2. In a cop winding machine, a thread brake and means for actuating the thread brake to increase the tension on the thread when forming the point of the cop; said brake having a pair of opposing disks and a spring for pressing them together, and said means comprising a two-armed lever acting against the disks in opposition to said spring and a cam engaging with the free end of said lever to oscillate it, thereby periodically compressing said spring.

3. In a cop winding machine, a pair of

guide members for the thread, said members having a stationary axis, manually adjustable means exerting axial pressure on said members, and automatic means including a centrally fulcrumed lever, said automatic means coöoperating with said first means for periodically increasing the tension on the thread while practically retaining its path, a cam engaging one end of said lever while

pressing its other end against one of said guide members.

The foregoing specification signed at Zurich, Switzerland, this sixth day of February, 1914.

HANS SCHWEITER.

In presence of—

HET. BAUMGARTNER,
W. THIRZEL.
